CLAIM

The ornamental design for a clamp on ultrasonic flow meter, as shown and described.

DESCRIPTION

FIG. 1 is a front right perspective view of a clamp on ultrasonic flow meter according to the present invention. The flow meter device is shown mounted on a pipe/tubing shown in dash lines, for purpose of illustration only.

FIG. 2 is a front view of the flow meter device shown in FIG. 1;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front right perspective view of the flow meter device of FIG. 1 according to the present invention but showing the flow meter device in an open configuration.

FIG. 9 is a front view of the flow meter device in the open configuration of FIG. 8.

FIG. 10 is a right side view of the flow meter device in the open configuration of FIG. 8; and,

FIG. 11 is a left side view of the flow meter device in the open configuration of FIG. 8.

The dash-dash broken lines represent portions of the article that form no part of the claimed design.

The dash-dot broken lines show break lines and the appearance of any portion of the article beyond the break lines forms no part of the claimed design.
